UNITED STATES PATENT OFFICE.

WILLIAM E. WHITE, OF CHICAGO, ILLINOIS, ASSIGNOR TO KALMAN STEEL COMPANY,
OF CHICAGO, ILLINOIS, A CORPORATION OF DELAWARE.

STAKE.

Application filed February 14, 1927. Serial No. 168,095.

My invention relates to stakes for use with road strips. Such strips are customarily provided with aligned openings in the laterally projecting rib, the strip being maintained in proper position prior to the pouring of the concrete by means of stakes adapted to pass through the openings and to enter the soil.

An object of the invention is to provide a stake which is adapted to function correctly without the necessity for accuracy in construction. In those stakes which are of larger diameter than the holes through which they are driven and which must be compressed during the driving action, slight inaccuracies in the dimensions of the stake or the holes serve to render the cooperation uncertain or difficult.

In the stake of my invention, there is no need for accuracy, except in that the stake must have its greatest diameter less than the diameter of the holes through which it is driven. In order to secure the requisite frictional holding capacity, I provide a resilient tongue, preferably struck out from the body of the stake, the tongue being deflected as the stake is driven into place.

The invention will be more readily understood by reference to the accompanying drawing, in which;

Fig. 1 is a perspective view of a section of road strips and a stake associated therewith;

Fig. 2 is a side elevation somewhat enlarged showing the stake in elevation, and the road strips in section;

Fig. 3 is a face view of the stake;

Fig. 4 is a view similar to Fig. 2, showing the stake in its final position, and

Fig. 5 is a plan view of the construction shown in Fig. 4.

In the drawings, the road strips are indicated at A, and the stake is at B. The strips have a V-shaped central rib, 10, two of the strips being overlapped and being provided with registering apertures, 11, for the reception of the stake B.

The stake of my invention is of arcuate form in cross section, having sides, 12, and a central portion, 13. The sides are diagonally sheared at the bottom to provide the pointed end.

At a point near the upper end, the body

portion, 13, is punched out to provide a tongue, 14, originally positioned as shown in Fig. 2. It will be seen that if the stake 55 is to assume the position of Fig. 4, the tongue must be laterally deflected by contact with the upper flange of the strip A, and this serves to frictionally hold the parts in proper relation, the tongue serving also as a stop 60 to define the downward limit of the stake.

The form of the stake and the exact location and arrangement of the tongue are unimportant, and I consider these and other modifications to be within the spirit of my 65 invention.

I claim:

1. A stake for road strips, comprising a length of metal and a tongue of metal extending longitudinally of the stake, located 70 near the upper end thereof and projecting laterally therefrom and adapted to be deflected by contact with the strip as the stake is driven.

2. A stake for road strips, comprising a 75 length of metal of generally channel shape in cross section, and a tongue of metal extending longitudinally of the stake, located near the upper end thereof and projecting laterally therefrom and adapted to be deflected by contact with the strip as the stake 80 is driven.

3. A stake for road strips comprising a length of metal having an integral tongue struck from the body of the stake near the 85 upper end thereof and projecting laterally therefrom and adapted to be deflected by contact with the strip as the stake is driven.

4. A stake of generally channel form in 90 cross section having a tongue struck out laterally from the body of the stake near the upper end thereof.

5. A stake for road strips, the largest 95 diameter of the body of the stake being less than the diameter of the holes in the strip into which the stake is to be received, and a tongue projecting laterally from the body of the stake near the upper end thereof and adapted to frictionally contact the strip and be deflected thereby as the stake is driven 100 through the holes in the strip.

In testimony whereof I have affixed my signature.

WILLIAM E. WHITE.
